AUTOMATIC ACOUSTIC CONTROL FOR PUBLIC ADDRESS SYSTEMS AND THE LIKE

Grant N. Wetzel, Cedar Rapids, Iowa, assignor
to Collins Radio Company, Cedar Rapids, Iowa,
a corporation of Iowa

Application January 24, 1946, Serial No. 643,161

4 Claims. (Cl. 179—1)

1

This invention relates to electrical voice frequency reproducing systems and more particularly to the regulation of the volume of a public address system or the like with respect to the acoustical noise level in the vicinity of the loudspeaker.

In public address systems used in the vicinity of electrically driven machines, such as in a machine shop or the like, the acoustic noise produced by the machines when in operation may be great enough to interfere with the intelligibility of the reproduced sound from the public address loudspeaker. In such cases, it is desirable, in order that intelligibility will be insured, to have some means of increasing the acoustic level of the loudspeaker output in proportion to the acoustic noise in the environs of the loudspeaker. I have found that this can be accomplished automatically by using the electric power line load current as the determining factor in controlling the acoustic output level of the loudspeaker.

Accordingly, it is an object of this invention to provide a public address system and the like, wherein the voice frequency output of a loudspeaker and the like is automatically increased as the acoustic noise level in the environs of the loudspeaker is increased.

It is also an object of this invention to provide an automatic acoustic volume control circuit for use in connection with a public address system wherein the acoustic output of the system bears a definite and predetermined relationship to the current in power supply conductors which supply power to electrically driven machinery in the vicinity of the public address system.

It is a further object of this invention to provide an automatic acoustic volume control public address arrangement wherein the volume of the reproduced sound is automatically adjusted in accordance with changes in the load current of the power supply system which feeds electrical equipment to be operated in the vicinity of the public address system.

A feature of this invention is that the automatic acoustic volume control may be made to have any desired relation to the current in the power supply system, by means of a relay-controlled attenuator.

Another feature of this invention is that the automatic volume control is achieved by the use of a small number of components and is controlled by the current in the power line supplying electric energy to the system.

Other objects, features and advantages not particularly enumerated, will be apparent after

2

a consideration of the following detailed description and the appended claims.

The drawing is a circuit diagram showing one preferred embodiment of the invention.

Referring more particularly to the drawing, conductors 1 and 2 convey energy from a suitable source 3 of commercial alternating current power supply to the area in which the loudspeaker of the public address system is located. These conductors may supply one or more electrically driven machines 4, 5 as well as supplying the power for the public address amplifier 6 connected to any source of voice frequency signals 7. Amplifier 5 may be of any well-known grid-controlled vacuum tube type. The power current transformer 8 is situated at some suitable place along one of the conductors 1, 2. The primary 9 of transformer 8 consists of one of the conductors 1, 2 here shown as conductor 2, coiled around the transformer core 10. The conductor 2 may be coiled for a plurality of turns around the core 10. It will be understood that any well-known current transformer may be used with its primary connected in series with one of the conductors 1, 2.

25 To prevent excessive voltage drop across the transformer, it is necessary to have the primary with as low a series reactance as possible. For this reason, the number of turns on the primary of the transformer should be small.

30 The output of transformer secondary 11 is fed to a rectifier 12 which may be of any suitable type, such for example as the well-known dry disc or copper oxide type. The potentiometer resistor 13 serves as the load resistor of rectifier 12. Condenser 14 is a smoothing condenser and removes the ripple from the output of rectifier 12. The winding of alternating current relay 15 receives a portion of the output of rectifier 12 in accordance with the setting of the movable arm 16 along resistor 13.

When the winding of relay 15 is deenergized, the contacts are in the positions illustrated and the amplifier 6 is connected to the loudspeaker 17 through the attenuator network 18 comprising resistors 19, 20 and 21. Attenuator 18 limits the acoustic output of the loudspeaker 17 and fixes it at a predetermined value, when relay 15 is deenergized. If desired, one or more of the resistors 19, 20, 21 may be manually adjustable. The inclusion of this attenuator or circuit with the loudspeaker is through the armatures 22, 23 and their respective back contacts 24, 25. When relay 15 is operated, the attenuator is removed from the circuit, and the wires 26, 27 are directly connected through armature 23 and front contact 28,

When the load current in power lines 1, 2 rises above a predetermined level, this rise in line current is sufficient to operate the contacts of relay 15. Thereupon the attenuator 18 is eliminated from circuit and amplifier 6 is directly connected to speaker 17. The elimination of attenuator 18 allows an increased amount of energy to be fed to loudspeaker 17 which increases its acoustic output proportionately. The acoustic volume output of the loudspeaker therefore is a function of the power load current supplied by lines 1, 2 to the neighboring electrical machinery.

If adjustable contact arm 16 is initially adjusted along resistor 13 and the connections are completed through contacts 24 and 25 a predetermined amount of attenuation occurs in network 18 and causes limitation of the acoustic volume output of loudspeaker 17. If the noise level increases, as is the case when line 1-2 supplies a greater load current, the amount of current flowing through relay 15 increases to a value sufficient to operate relay 15 and thereby eliminate attenuator 18 from the circuit as heretofore described. The acoustic volume output of loudspeaker 17 immediately increases thereby compensating for the increase in noise level.

The use of a single relay as above described allows operation of the loudspeaker at two different volume outputs. The use of a series of such marginal relays and associated attenuators will afford operation of the loudspeaker at a series of different volume levels. The number of relays used in each case is determined among other things by the probable noise level, and each relay will be marginally wound to respond successively to different values of line load current.

While there has been here described a preferred embodiment, it will be understood that various changes and modifications may be made therein without departing from the scope of the invention. Thus the invention is not limited to use with A. C. supply mains but may be used with D. C. mains. In that event, the relay 10 may be connected directly in series with the line 1-2 or, if desired, it may be shunted across a load resistor which is connected directly in series with the line 1-2.

What is claimed is:

1. In a sound reproducing system, a voice-frequency controlled amplifier, a sound reproducer supplied from said amplifier, alternating current supply mains for supplying operating power to electrically driven machines located in the vicinity of said reproducer, a current transformer connected in series with said mains, a rectifier and potentiometer combination connected across the output of said transformer, an electro-magnetic relay having its winding connected to said potentiometer, said relay having contact sets for selec-

tively connecting a voice frequency signal attenuator in circuit between said amplifier and reproducer.

5 2. The method of operating a public address amplifier and reproducer system for use in the vicinity of noise producing machines electrically driven from power supply mains and whose noise level is proportionate to the load current in said mains drawn by said machines, which comprises adjusting the level of the amplifier output in accordance with a predetermined load level current in said mains and automatically varying the level of the amplifier output in accordance with variations in said load current in said mains.

10 3. In a sound reproducing system for use in the vicinity of power machines electrically driven from power current supply mains and whose noise producing level is proportionate to the load current in said mains drawn by said machines, said system having an amplifier, a sound reproducing device connected to the output of said amplifier, a load current transformer the primary of which is in series with said power mains, a rectifier connected in circuit with the secondary of said transformer, a variable resistor in parallel with a condenser connected to the output of said rectifier and across the secondary circuit of said transformer, a relay connected across said variable resistor, an attenuator connected between said 15 amplifier and said device and arranged to be switched into and out of circuit by said relay, said relay being responsive to the magnitude of the rectified current in the output of said rectifier.

20 4. In a sound reproducing system for use in the vicinity of power machines electrically driven from current supply mains which machines produce a noise level proportionate to the amount of current in said mains drawn by said machines, said system comprising an amplifier, a loud 25 speaker, an automatic acoustic volume control for said speaker comprising a relay, circuit connections for selectively operating said relay in accordance with the levels of the load currents drawn by said machines, and an attenuator automatically connectable by said relay between said 30 amplifier and said loud speaker.
